L. M. WOOLSON.
HYDROCARBON MOTOR.
APPLICATION FILED DEC. 29, 1919.

1,424,430.

Patented Aug. 1, 1922.

UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

1,424,430.

Specification of Letters Patent. Patented Aug. 1, 1922.

Application filed December 29, 1919. Serial No. 348,053.

To all whom it may concern:

Be it known that I, LIONEL M. WOOLSON, a citizen of the United States, and resident of Detroit, Wayne County, State of Michigan, have invented certain new and useful Improvements in Hydrocarbon Motors, of which the following is a specification.

This invention relates to hydrocarbon motors, and particularly to carbureting and mixture heating devices therefor.

One of the objects of the present invention is to provide improved means for supplying a combustion heater with a portion of the mixture from the motor carburetor.

Another object of the invention is to provide a novel form of carburetor and heater device of very simple construction.

Another object of the invention is to provide a novel form of spray device for the mixture upon its entrance to the combustion chamber.

Other objects and advantages of the invention will appear from the following description taken in connection with the drawings which form a part of this specification, and in which—

Figure 1 is substantially a vertical section through a carbureting and mixture heating device embodying the invention;

Figure 2 is a section substantially on the line 2—2 of Figure 1; and

Figure 3 is a section on the line 3—3 of Figure 1.

In some combustion heaters of the suction type it has heretofore been proposed to provide a separate carburetor for supplying a suitable mixture to the heater, and in others a mixture withdrawing means has been inserted into the mixing chamber for taking therefrom some of the mixture supplied by the main carburetor for operating the heater.

The separate carburetor construction requires a number of additional parts, thereby making it more expensive, and the mixture withdrawing means heretofore used have not been found to be thoroughly successful at all speeds of the motor. It is believed that the faults in these previous constructions are in the arrangement and construction of the mixture withdrawing means, and it is believed that the present invention overcomes the objections to prior devices of this type.

The success of the present construction, so far as the mixture withdrawing means is concerned, depends upon the location of the inlet opening for the heater either substan-

tially symmetrically above the mixture making part of the carburetor and facing downwardly towards the carburetor, or in the arrangement of such opening at the bend in the mixture conduit. By this location the opening receives a portion of the best mixture produced by the carburetor and the portion of the mixture which it withdraws is thereupon conveyed to the combustion heater, which thereby operates substantially perfectly and automatically as is theoretically demanded.

Referring to the drawings of the embodiment of the invention herein shown, a fragment of a cylinder block of a hydrocarbon motor is shown at 10, and 11 is the passage leading to the intake valves of the cylinder or cylinders. 12 is an elbow or casting having a substantially horizontal part 13 and a substantially vertical part 14. In the horizontal part is arranged the motor throttle 15 controlled by an operating arm 16, and a flange 17 is provided for securing the elbow to the motor cylinder 10 so that its horizontal passage registers with the passage 11 thereof.

At the lower end of the vertical part 14 of the elbow 12 is arranged the carbureting means, and the particular means herein shown is of the well known Stewart form as used on the Dodge motor. In general it comprises a float chamber 18 supplied by a pipe 19, and in which is a float 20 controlling a valve 21 in the usual way. A channel 22 from the float chamber leads to a well 23 in which a hollow piston 24 is arranged to vertically move. The piston has one or more check valves 25 in its face so that it may act as a dashpot in moving upwardly, but may move downwardly quite freely. In the vertical passage 25 through the stem 27 of the piston 24 is a tapered needle valve 28 which may be manually adjusted as by a lever 29 and gears 30 for thus adjusting the size of the fuel passage in said piston. Ports 31 permit the passage of fuel to the interior of the stem 27.

The stem 27 is slidably mounted in a vertical guide 32 which extends upwardly through an air chamber 33 having an inlet opening 34 through which the carburetor receives all of its air. At its upper end the stem 27 carries a conical shaped air valve 35 which normally rests on a seat 36, and the passage 26 has a flared nozzle 37 at its upper end. The valve 35 has air passages

38 and 39 leading to an air passage 40 which surrounds the outlet of the nozzle 37. Thus the fuel or spray nozzle 37 and the passage 40 are symmetrically arranged in the valve 5 35, which valve may be moved upwardly from its seat by the suction in the chamber 41 above the valve to thereby supply an additional amount of air for the mixture. The chamber 41, therefore, which is the vertical part of the elbow 12, is the mixing chamber 10 of the carburetor and as the valve 35 moves upwardly under suction to supply additional air, the stem 27 upon which the air valve is mounted also moves upwardly relative to the tapered pin 28 and thereby increases the size of the fuel opening or passage in the stem 27. Thus a substantially correct proportion of fuel and air is supplied by the carburetor at all speeds of the 15 20 motor.

Arranged vertically and symmetrically above the fuel nozzle 37 and its adjacent air passage 40 and at the upper end of the mixing chamber 41 is the inlet opening 42 for 25 the combustion heater. This opening is shown also as arranged in the bend of the elbow 12 and it faces downwardly towards the carbureting means in the lower part of the mixing chamber 41, and by reason of 30 its separation at some distance from said carbureting means and above the latter and in the bend of the elbow, it is adapted to receive a homogeneous mixture of gasoline and air with which to supply the combustion 35 heater. A channel 43 connects the opening 42 with a contracted passage 44 which determines the amount of mixture to be supplied to the combustion chamber. The passage 44 communicates with a larger 40 vertical passage 45 at the upper end of the latter and extends into it tangentially as shown particularly in Figure 3. The lower end of the vertical cylindrical channel 45 opens into the combustion chamber 46 a 45 short distance above a screen 47 which extends across the chamber at that point and also directly above a spark plug 48 which is adapted to deliver a spark for firing the mixture in the chamber 46.

50 By this tangential arrangement of the passage 44 relative to the vertical passage 45, the gas entering the chamber 45 is given a swirl or spiral motion downwardly and the gas spreads at the lower end of the passage 45 as it strikes the screen 47. The screen further divides the particles of fuel that may be present in the mixture so that a still better mixture is drawn downwardly towards the spark plug 48 where it is readily 55 60 fired.

The outlet from the combustion chamber 46 is through a rather wide passage 49 and a pair of diagonally arranged passages 50 which extend on either side of the elbow 12 65 and to points 51 beyond the motor throttle

valve 15 where they communicate with the interior of the horizontal part of the elbow and receive the full suction of the motor. Thus the hot gases passing through the channels 49 and 50 tend to heat the casting 70 forming the elbow 12 and as they are drawn into the motor intake passage they come in direct contact with the mixture therein and heat it to a point where it is readily ignited in the cylinders. 75

The combustion chamber 46, in the form shown in the drawings, is in a casting 52 which is detachably secured to the elbow 12 as by two pairs of bolts 53 and 54 and a plug 55 is threaded into the upper part of 80 the casting and in this plug is formed the passage 45 and part of the passage 44, the other part of the passage 44 being formed directly in the casting 52, as shown in Figures 1 and 3. The screen 47 is retained in 85 place by this plug 55. A window 56 is also arranged in the casting 52 so that the action of the heater may be observed.

It will be understood that the form shown herein is illustrative only of the invention, 90 and various modifications thereof may be made without departing from the spirit or scope of the invention as defined by the claims.

Having thus described my invention, what 95 I claim and desire to secure by Letters Patent is:

1. In a hydrocarbon motor, the combination with the motor cylinder, of a carburetor and heater device comprising an elbow having a substantially horizontal part for connection to the motor cylinder and a substantially vertical part for connection to the carburetor, a carburetor connected to said vertical part of the elbow, a throttle 100 valve arranged in the horizontal part of the elbow, and a combustion heater having its inlet opening arranged at the bend in the elbow. 105

2. In a hydrocarbon motor, the combination with the motor cylinder, of a carburetor and heater device comprising an elbow having a substantially horizontal part for connection to the motor cylinder and a substantially vertical part for connection to 115 the carburetor, a carburetor connected to said vertical part of the elbow, a throttle valve arranged in the horizontal part of the elbow, and a combustion heater having its inlet opening arranged at the bend in the 120 elbow and its outlet opening between said throttle valve and the motor cylinder.

3. In a carburetor and heater device, the combination of a substantially right angle elbow having vertical and horizontal branches, 125 carbureting means secured to the lower end of the vertical branch of said elbow, a combustion heater, and means for withdrawing a portion of the mixture from said elbow for said heater, said means comprising an 130

inlet opening arranged at the bend of said elbow.

4. In a carburetor and heater device, the combination of a substantially right angle elbow having vertical and horizontal branches, carbureting means secured to the lower end of the vertical branch of said elbow, a combustion heater, and means for withdrawing a portion of the mixture from said elbow for said heater, said means comprising an opening arranged substantially at the highest point in the elbow above said carbureting means.

5. In a carburetor and heating means, the combination of a mixture chamber, fuel and air inlets symmetrically arranged at the lower part of said chamber, and a combustion heater having its mixture inlet opening symmetrically arranged vertically above said fuel and air inlets and at the upper end of said chamber.

6. In a carburetor and heating means, the combination of a mixing chamber forming an elbow at its upper end, fuel and air inlets symmetrically arranged at the lower part of said chamber, and a combustion heater having its mixture inlet opening symmetrically arranged above said fuel and air inlets and at the bend of said elbow.

7. In a carburetor and heater device, the combination of a mixing chamber, carbureting means at the lower part of said chamber, and a combustion heater having its inlet at the upper part of said chamber and having outlet channels extending around said mixing chamber to a point beyond the motor throttle valve.

8. In a carburetor and heater device, the combination of a mixing chamber, carbureting means at the lower part of said chamber, and a combustion heater having its inlet at the upper part of said chamber and having outlet channels extending along the sides of said mixing chamber.

9. In a carburetor and heating device, the combination of a mixing chamber, carbureting means connected thereto, a combustion chamber arranged at one side of the mixing chamber, an inlet conduit for the combustion chamber extending from the upper part of the mixing chamber to the up-

per part of the combustion chamber and opening downwardly thereinto, an outlet conduit extending from the lower part of the combustion chamber along one side of the mixing chamber to a point beyond the motor throttle, and an ignition device for the combustion chamber.

10. A combustion heater comprising a combustion chamber and spray means at the upper part of said chamber and communicating therewith, said spray means comprising a vertical cylindrical passage opening into the combustion chamber and a horizontal contracted mixture inlet passage connecting with said vertical passage and tangential to the cylindrical wall thereof.

11. A combustion heater comprising a combustion chamber and spray means at the upper part of said chamber and communicating therewith, said spray means comprising a vertical cylindrical passage opening into the combustion chamber and a horizontal contracted mixture inlet passage connecting with said vertical passage and tangential to the cylindrical wall thereof, and a screen in the combustion chamber beneath the lower end of said vertical passage.

12. In a carburetor and heating means, the combination of a substantially right angle elbow having vertical and horizontal branches, carbureting means at the lower end of the vertical branch of said elbow and having fuel and air inlets symmetrically arranged relative to said vertical branch, a combustion heater, and means for withdrawing a portion of the mixture from said elbow for said heater, said means comprising an inlet opening arranged at the bend of said elbow and vertically above said fuel and air inlets.

13. In a carburetor and heating means, the combination of a substantially right angle elbow, carbureting means connected to the inlet end of said elbow, a combustion heater, and means for withdrawing a portion of the mixture from said elbow for said heater, said means comprising an inlet opening arranged at the bend of said elbow.

In testimony whereof I affix my signature.

LIONEL M. WOOLSON.
